(57) **CLAIM**

The ornamental design for an art and animation light box, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front right perspective view of the design of the art and animation light box;

FIG. 2 is a front elevational view of the art and animation light box;

FIG. 3 is a rear elevational view of the art and animation light box;

FIG. 4 is a right side elevational view of the art and animation light box;

FIG. 5 is a left side elevational view of the art and animation light box, and is a mirror image of the view illustrated in FIG. 4;

FIG. 6 is a top plan view of the art and animation light box;

FIG. 7 is a bottom plan view of the art and animation light box;

FIG. 8 is a front right perspective view of a second embodiment of the design of the art and animation light box;

FIG. 9 is a front elevational view of the art and animation light box of FIG. 8;

FIG. 10 is a rear elevational view of the art and animation light box of FIG. 8;

FIG. 11 is a right side elevational view of the art and animation light box of FIG. 8;

FIG. 12 is a left side elevational view of the art and animation light box, and is a mirror image of the view illustrated in FIG. 11;

FIG. 13 is a top plan view of the art and animation light box of FIG. 8; and,

FIG. 14 is a bottom plan view of the art and animation light box of FIG. 8.

FIGS. 1-7 are directed to a translucent art and animation light box, and FIGS. 8-14 are directed to a transparent art and animation light box.
